(No Model.)

S. L. BEAN.
ROLLER GRINDING MILL.

No. 258,877.

Patented June 6, 1882.

Inventor:
Samuel L. Bean
by his Attorney
Ed. C. B.

UNITED STATES PATENT OFFICE.

SAMUEL L. BEAN, OF WASHINGTON, DISTRICT OF COLUMBIA.

ROLLER GRINDING-MILL.

SPECIFICATION forming part of Letters Patent No. 258,877, dated June 6, 1882.

Application filed July 13, 1881. (No model.)

To all whom it may concern:

Be it known that I, SAMUEL L. BEAN, a citizen of the United States, residing at Washington, District of Columbia, have invented 5 certain new and useful Improvements in Roller Grinding-Mills; and I do hereby declare the following to be a full, clear, and exact description of the invention, such as will enable others skilled in the art to which it appertains to make 10 and use the same, reference being had to the accompanying drawings, and to the letters or figures of reference marked thereon, which form a part of this specification.

Heretofore it has been customary to subject 15 the chop in its transit from one set of grinding-rollers to the next succeeding set to a screening operation by passing it over a reciprocating screen or through a rotating bolt, or through a stationary concave screen co-operating 20 with fan-beaters. In every case the chop is subjected to a great deal of attrition comparatively, which tends to separate fine yellow flakes from the coarser particles and mix them with the flour and middlings.

25 The object of my invention is to subject the chop to as little attrition as possible in separating the flour and middlings from it in its passage from one pair of grinding-rollers to the next pair, and thus prevent the detachment 30 of yellow dust from the bran and its admixture with the flour and middlings as far as practicable.

To this end my invention consists mainly 35 in the use of one or more rotating cylindrical screens, arranged under a pair of grinding-rollers, for separating the flour and middlings from the chop, which is to fall onto the exterior surface of such rotating cylindrical screen or screens on its way to the next pair of rollers.

40 It further consists of the combination, with each rotating cylindrical screen, of a trough for conveying away the separated flour and middlings and a brush for cleaning the meshes of the screen.

45 In order that my invention may be clearly understood, I have illustrated in the annexed drawings and will proceed to describe the best form thereof at present known to me as applied to a roller grinding-mill containing four 50 pairs of grinding-rollers.

Figure 1 is a vertical transverse section of a roller grinding-mill embodying my invention.

Fig. 2 is an axial section through one of the screens.

The drawings represent a roller grinding- 55 mill constructed with four pairs of grinding-rollers, A A', with separating-screens intermediate between each two pairs of rollers, so that the grain is subjected to a fourfold grinding and the chop to a threefold separation. Fur- 60 thermore, I have shown three screens between each two pairs of grinding-rollers, so that the separation between each grinding is divided over three screens. This division of separa- 65 tion is not essential, although I regard it as preferable, and a single screen only may be used; or the number of screens may be increased after each grinding, one being used, for instance, under the first pair of grinding-rollers, two under the second pair, and so on. The 70 thing required is to accommodate the separating capacity of the screen or screens to the amount of flour and middlings produced at each grinding.

The screens B are cylindrical and made of 75 sieve-cloth of required mesh. They are hung on shafts or journals and are rotated in any suitable manner in the directions of the arrows. The chop is directed from the grinding-rollers above by a chute, a, if necessary, toward the 80 axis of the cylindrical screen and onto the exterior surface thereof, so as to spread over the screen and permit the flour and middlings to pass through its meshes into the interior of the screen. In consequence of its rotation the 85 screen constantly presents fresh surface to the chop. When more than one rotating cylindrical screen is used under a single pair of grinding-rollers, I prefer to arrange such screens stepwise, as shown, so that the chop may fall 90 from one directly onto the next one, and from the lowermost one directly between the next pair of grinding-rollers. The separated flour and middlings are received by a trough, C, preferably arranged within the rotating cylind- 95 rical screen, though it may be suspended beneath the same. This trough may contain a conveyer to carry away the separated flour and middlings; or it may be arranged slant- 100 ingly and vibrated endwise for discharging such flour and middlings. The rotating cylindrical screens may also be vibrated endwise, so as to jar them somewhat to aid the separation.

In order to clean the meshes of the rotating

cylindrical screens, a brush, D, (one or more,) is applied to each, preferably a rotating brush arranged to brush the exterior side of the screen. Air-currents are also drawn through the chest 5 and through the chop and screens to carry off the dust and light flour; but I make no claim to this feature, nor to any other feature of this roller grinding-mill, except the rotating cylindrical screens and the combinations thereof.

10 In fact, I illustrated my invention as embodied in a roller grinding-mill of the general type exemplified in United States Letters Patent No. 248,578. The rotating cylindrical screens and brushes may be driven by belt-gearing, 15 cog-gearing, or friction-gearing of any known construction. I make no claim to the means for rotating these devices, and any person skilled in the art can readily apply such means for rotating them.

20 The screen B may be supported and driven as shown in Fig. 2, the head of the screen at one end being keyed to a journal, b, which passes through a bearing on the chest A, and is provided with a pulley, b', so that the screen 25 may be rotated thereby, the other head of the screen being supported on the end of the bearing on the opposite side of the chest, so as to turn on said bearing. The slanting trough C is suspended at one end from the journal b by 30 a link adapted to slide on the journal. The other end of the trough is rigidly attached to a sliding rod, b², passing through the bearing on which the screen turns, its outer end being secured to a spring, b³, fastened to the chest 35 and provided with a pin, b⁴, extending through the side of the chest, so that it may be operated upon by a cam-surface, c, formed on the head at this end of the screen. Thus the cam-surface will periodically force the pin b⁴ and 40 the spring b³ to which it is attached outward, and as soon as the pin b⁴ escapes from the cam c the spring b³ will recoil, and thus the trough C will be reciprocated endwise to discharge the middlings and fine flour through the opposite head of the screens upon a cant-board 45 which directs such middlings and flour to an opening in the chest, as shown in Fig. 2.

Having thus described my invention, what I claim is—

1. The combination, substantially as before 50 set forth, of a pair of grinding-rollers and a rotating cylindrical screen, onto the exterior surface of which the chop from the grinding-rollers falls.

2. The combination, substantially as before 55 set forth, of a pair of grinding-rollers and a series of rotating cylindrical screens, onto the exterior surface of which the chop from the grinding-rollers falls, arranged stepwise, so that the chop shall pass from the exterior surface of one down upon the next.

3. The combination, substantially as before 60 set forth, of a pair of grinding-rollers, a rotating cylindrical screen, onto the exterior surface of which the chop from the grinding-rollers falls, and a brush at a point outside of the flow or current of chop.

4. The combination, substantially as before 65 set forth, of a pair of grinding-rollers, a rotating cylindrical screen, onto the exterior surface of which the chop from the grinding-rollers falls, and a shaking-trough for conveying away the particles-separated from the chop by the rotating screen.

5. The combination, substantially as before 70 set forth, of a pair of grinding-rollers, a rotating cylindrical screen, onto the exterior surface of which the chop from the grinding-rollers falls, and a shaking-trough within the screen.

6. The combination, substantially as before 75 set forth, of a pair of grinding-rollers, a rotating cylindrical screen, onto the exterior surface of which the chop from the grinding-rollers falls, a shaking-trough within the screen, and a brush operating on the screen at a point outside of the flow or current of chop.

In testimony whereof I affix my signature in presence of two witnesses.

SAML. L. BEAN.
